UNITED STATES PATENT OFFICE.

FREDERIC S. CONVERSE, OF BINGHAMTON, NEW YORK.

COAL-LOADING MACHINE.

1,133,008.

Specification of Letters Patent. Patented Mar. 23, 1915.

Application filed August 10, 1914. Serial No. 856,023.

To all whom it may concern:

Be it known that I, FREDERIC S. CONVERSE, a citizen of the United States, residing at Binghamton, in the county of Broome and State of New York, have invented certain new and useful Improvements in Coal-Loading Machines; and I hereby declare that the following is a full, clear, and exact description thereof, reference being had to the accompanying drawings, which form part of this specification.

This invention is a novel machine designed for loading various materials such as coal from piles into wagon or other conveyances, and to screen the material between the pile and the point of discharge.

It comprises in brief a novel adjustable elevator for removing the material from the pile; novel screening mechanism whereby the material can be screened and graded; and different grades discharged if desired at different points; and the screenings separately discharged; and a novel construction whereby the parts may be partially collapsed or folded when desired. These and other minor features of the invention will be clearly understood from the following description thereof in connection with the accompanying drawings, which illustrate one practical embodiment of the invention; and I refer to the claims for summaries of the features and combinations of parts for which protection is desired.

In said drawings:—Figure 1 is a right hand side elevation of the complete machine. Fig. 2 is a left hand side elevation thereof. Fig. 3 is a sectional plan view on line 3—3, Fig. 2. Fig. 4 is a left hand side elevation showing the machine collapsed or folded. Fig. 5 is a detail top plan view of parts of the machine partly broken. Fig. 6 is a detail end view of Fig. 5. Fig. 7 is a detail plan view of the hopper 5. Fig. 8 is a detail sectional view of the hopper and screen.

The operative parts of the machine are preferably mounted upon a base frame 1 which may be made of any suitable material, and mounted upon rear wheels 1^a; and front wheels 1^b attached to an axle 1^c which is pivotally connected to the frame in the usual manner. Upon this frame 1 are mounted two front standards, each composed of upper and lower bars 1^e, 1^f, jointed together at 1^g; and two rear standards each composed of

two bars 1^h and 1ⁱ pivoted together at 1^j, so that the frame may be folded or tilted as hereinafter explained. The lower ends of bars 1^e are also pivoted to the frame as at 1^k. To the upper ends of the bars 1^h, 1ⁱ of the standards are attached bars 1^m and these parts may be braced by bars 1ⁿ so as to form a suitable strong and stiff main supporting frame for the operative parts.

Attached to the upper end of the bars 1ⁱ are bearings 2^a for a transverse shaft 2 which extends across the frame as shown; and upon this shaft is hingedly supported the upper end of an endless elevator which comprises a frame 3 which is preferably constructed of metal bars, as indicated in the drawings, and has bearings 3^a attached to its rear member, which bearings are transfix by the shaft 2 and suspend the elevator frame thereon. The frame 3 has bearings 3^b at top and bottom for transverse shafts 3^b and 3^c on which are mounted sprocket wheels 3^d and 3^e over which runs an endless sprocket chain 3^f carrying elevator buckets 3^g which descend at the inner side of the elevator and ascend at the outer side thereof, and are adapted when in operation to scoop up coal, or other material from a pile at the bottom, and carry the same to the top of the machine and discharge it into a hopper 5 thereon. The endless conveyer or elevator is operated as hereinafter explained.

To the lower end of the elevator frame are attached bars 4, see Fig. 3, which may be guided in loops 4^a on the rear bar of the frame 1, and these bars may be toothed or perforated as indicated in Fig. 3 to engage gears or spur wheels 4^b attached to the shaft 4^c journaled in bearings on the frame 1 (see Fig. 3) and which shaft may be operated by means of a spur gear 4^d connected by a chain 4^e with a sprocket 4^f, on a shaft 4^g journaled in bearings on the frame 1, and having a sprocket 4^h driven by a chain 4ⁱ from a sprocket 4^j on a stub shaft 4^k suitably journaled on one of the rear uprights 10 of the frame, and which can be operated by means of a crank handle 4^m.

In addition to crank 4^m for operating shaft 4^k I provide a hand lever 4° (Figs. 2 and 3) which may be loosely pivoted on said shaft 4^k beside a notched disk 4^l keyed to said shaft, and the lever can be locked to said disk by means of a spring catch 4ⁿ,

operated by a hand piece 4^r on the lever 4° in the usual manner, so that instead of using the crank 4^m a person in the wagon being loaded may shift the conveyer by manually operating lever 4°.

The lower end of the frame 3 can be swung to or from the frame 1 so that it can be introduced into a pile of coal, or other material to be lifted by the buckets, and kept 10 in proper operative contact with such pipe without the necessity of moving the entire machine in order to follow up the decreasing pile of coal.

The endless series of buckets 3^g may be 15 operated by means of a sprocket wheel 3ⁿ on shaft 3^c (Figs. 1 and 2) driven by a chain 3^m from a sprocket 3^o on the shaft 2^o; and said shaft 2 may be driven by means of a sprocket 2^b thereon connected by a chain 2^c 20 with a sprocket 2^e on a shaft 2^d (Fig. 3) journaled in suitable bearings on the frame 1; and shaft 2^d in turn may be driven by a pulley 2^x operated by a belt 2^t from a pulley 2^g on the shaft of an electric or other motor 2^h mounted on the frame 1. I preferably 25 employ an electric motor where the machine is to be used in yards where electric power is readily obtainable, but any suitable motor may be used in place of an electric motor as 30 is obvious.

The coal elevated by the buckets 3^g is dumped into a hopper 5 on the top of the frame (see Figs. 1-2) and into a rotary screen 5^a (Fig. 5) which is of any desired 35 construction and is mounted on a shaft 5^b journaled in bearings 5^c and 5^d on the top members of the upright frame. The hopper 5 into which the coal is discharged from the buckets is preferably so constructed (see 40 Figs. 2 and 7) that there is constantly a quantity of coal in the bottom of this hopper onto which the coal discharged by the buckets drops, so that instead of the coal having to drop upon a metal surface, it 45 drops upon other coal which reduces fracture or breakage thereof. The coal heaps up on the bottom of the hopper 5 until the upper coal slides from the top of the pile in the hopper into the end of the rotary screen 5^a. On the same shaft 5^b and surrounding 50 the screen 5^a is a finer or rotary sieve 5^e which is spaced apart from screen 5^a by means of suitable studs 5^x, see Fig. 6, and the screens rotate together. The inner 55 screen 5^a has a mesh of a size so as to screen out coal, of any desired size, and the outer screen 5^e is so fine that only dust or waste will pass therethrough. These screens are 60 preferably rotated as follows: On the inner end of the shaft 5^b adjacent its bearing 5^d (see Figs. 5 and 6) is a sprocket 5^f which is driven by a chain 5^g from a sprocket 5^h on a stub shaft 5ⁱ on which may be a bevel 65 gear 5^j (Fig. 1) meshing with an opposed

bevel gear 5^k on a stub shaft 5^l which shaft has on its outer end a gear 5^m meshing with a bevel gear 2^m on shaft 2.

The screen 5^a discharges at the front end of the machine into a chute 6 which directs 70 coal into a foldable chute 6^a which is hinged at 6^b on brackets 1^o attached to the front standard 1^t, as indicated in the drawings, so that the chute 6^a may be folded up if desired. When the chute 6^a is lowered coal 75 can be discharged therefrom directly into a wagon being loaded, or into bags if desired. The chute 6^a may be provided with a gate 6^c (see Figs. 1 and 5) which can be lowered when the desired quantity of coal has been 80 delivered to the wagon or bags so as to stop the escape of coal through the chute 6^a, and if the operation of the machine is not stopped surplus coal will then pile up in the chute 6 until it begins to escape through 85 a passage 6^d in the side of the chute 6 (Fig. 5) whence it passes into a trough 6^e attached to the side of the frame, and which conducts the surplus coal back to the rear of the machine and discharges it onto the pile. The 90 coal that passes through the screen 5^a is caught in the screen 5^e, and the coarser screenings are discharged from the screen 5^e into the mouth of a chute 7, arranged at the discharge end of the screen 5^e (Figs. 1-5) 95 and is directed into a rotary screen 7^a, of ordinary construction, supported upon a shaft 7^b journaled in bearings attached to brackets 1^p on the side of the main frame, as indicated in Figs. 1 and 2. This screen 7^a 100 preferably divides the fine coal into two or more sizes if desired which are dropped from the screen into a hopper 7^c, which is shown as divided by an interior partition 7^d into two chambers, each of which may be respectively provided with sliding gates or valves 7^e and 7^f, so that the different grades of coal escaping from screen 7^a may be separated and retained in said compartments 105 from which they may be withdrawn at will. The screen 7^a may be rotated by means of a sprocket 7^h (Fig. 1) on its shaft 7^b driven by a sprocket chain 7ⁱ from a sprocket 5ⁿ on shaft 5^l.

The fine dust which escapes through the screen 5^e is caught in a hopper 5^q in which it can be trapped and retained until it is desired to discharge same: the lower end of this hopper 5^q being closed by a slide or gate 110 5^r, as indicated in the drawings, (Figs. 2 and 4).

When the machine is to be used it should be backed up against the pile of coal, or material to be screened, so that the lower end 115 of the endless conveyer enters the pile; and then started in operation and wagons or bags can be loaded with the coal discharged from the chute 6^a. As the coal pile is reduced the operator, by properly turning 120 125 130

shaft 4^a swings the lower end of the conveyor into the pile, without having to move the machine, until the pile is substantially removed. When the desired amount of coal has been loaded he can cut off the supply of 5 coal to the wagons by lowering the gate 6^a, and can either stop the motor, or withdraw the buckets from the pile by properly turning shaft 4^b.

The endless elevator so constructed that its 10 lower end may be pushed out to swing into the pile of coal as the latter is removed without having to back up the entire machine, or move the entire machine against the coal, is a very useful, practical and advantageous 15 feature of the invention.

The uprights of the frame might be rigid, but I preferably form them in sections and pivotally unite them as described so that the 20 top portion of the machine may be lowered or tilted forward, as indicated in Fig. 4, so that the machine may be more readily transported or drawn under shelter or sheds, or through a door-way. As shown in Figs. 1 25 and 2 the front uprights are formed in two sections pivoted at 1^b and the rear uprights are formed in two sections pivoted at 1^a. Attached to the rear end of the frame adjacent the bars 1^a and rigidly connected therewith are uprights 8, (Fig. 4) to the 30 upper ends of which are attached curved rack plates 8^a which are curved forward on an arc concentric with the pivots 1^a and the forward ends of these racks 8^a are connected to the front of the machine below the pivots 1^b, as indicated in Fig. 4. Journaled in bearings attached to the bars 1^a is a transverse shaft 9 on which are mounted spur gears 9^a which engage the segmental racks 35 or perforated plates 8^a. The shaft 9 may be rotated by means of sprocket pinions 9^b thereon connected by sprocket chains 9^c to sprockets 9^d on a stub shaft 9^e attached to the lower portion of the bars 1^a adjacent the 40 pivots 1^b, and said shaft 9^e is provided with a crank handle 9^f by which it may be turned.

When the machine is in operative upright condition, as shown in Figs. 1 and 2, the bars 1^a, 1^b may be locked in upright position 50 by means of bolts 1^g which may be engaged with corresponding registering openings 1^h in the parts 1^a, 1^b of the rear standards (Fig. 4) and prevent accidental folding of the frame. The shaft 9^e may also be locked by 55 any suitable means. When however it is desired to lower or fold the machine, for transportation or to run it into a shed, the bolts 1^g should be removed, and then shaft 9 turned, by crank 9^f, so as to cause the spur 60 gears 9^a to descend along the curved racks 8^a and lower the operative parts of the machine to the position shown in Fig. 4, the bars 1^a, 1^b folding toward each other, and the elevator frame being lowered to almost horizontal 65 position, as illustrated in Fig. 4. To

facilitate the lowering of the elevator frame, its lower end may be detached from the bars 4 by removing the bolts 4^x connecting the lower end of the frame 3 to the bars 4. When it is desired to put the machine in operative position the crank 9^f is turned so as to cause the spurs 9^a to roll up on the racks 8^a and raise the frame to vertical position and in such position the shaft 9^a should be locked and the bolts 1^g be inserted, thus holding the parts securely in operative position, and the bolts 4^x replaced to connect bars 4 to frame 3. 70

The bars 1^a, 1^b at the left hand side of the machine preferably fold backward, as 80 indicated in Fig. 4, so as not to interfere with the chute 6^a on the left, but the bars 1^a, 1^b, at the right hand side of the machine preferably fold forward so as not to interfere with the chute 7 on the right leading 85 into the small rotary screen 7^a.

The mode of operation of the machine will be sufficiently clear from the foregoing description and the drawings. With this machine the lower end of the elevator is movable to and from the pile of coal being loaded, and can be operated by the driver in the wagon, or by a man on the ground. It provides a combination loader and screen having chutes adapted either for loading or 90 for bagging coal. The novel hopper 5 lessens the danger of the coal breaking and the trough 6^a will carry away the overflow if it is discharged from the rotary screen 5^a faster than it can be bagged; or when the 95 valve or gate 6^a in the chute is closed and stops the flow of coal into the wagon or bag; the machine is also foldable or adjustable in height as described so that it can be lowered to facilitate its loading onto a car or 100 passing through a door.

The machine as shown will take coal from a mixed pile if desired and separate the small coal from the coal to be loaded, and from the dirt and smaller coal, at the same 110 time it will separate the fine coal from the dirt, and will grade very fine coal such as "chestnut" and "pea" coal; and will also if desired retain the dirt and dust so that the yard will not be littered by the operation of the machine; and because of the capability of the elevator being projected into the pile of coal it is not necessary to keep moving the machine up toward the pile of coal being loaded during the process of 115 loading.

While I have referred to this machine as a "coal loader," yet it is obviously adapted for use for loading, screening and sorting, sand, gravel or other substances without departing from the spirit and scope of the invention. 125

What I claim is:

1. In a machine of the character described, the combination of a base frame having ver- 130

tical uprights composed of sections pivotally connected together, arc-shaped rack bars at the sides of the frame, spur gears engaging said bars, a shaft rotatably connected with 5 opposite uprights and carrying spur gears engaging said bars, and means for rotating said shaft so as to cause the gears to ride up or down on said racks to raise or lower the frame.

- 10 2. In a machine of the character described, the combination of a base, a frame having vertical uprights comprised of sections pivotally connected together, arc-shaped rack bars at the sides of the frame, spur gears 15 engaging said bars, a shaft rotatably connected with opposite uprights and carrying spur gears engaging said bars, and means for rotating said shaft so as to cause the gears to ride up or down on said racks 20 to raise or lower the frame, with a conveyer frame mounted on said main frame and adjustable therewith, and means for adjusting the lower end of said conveyer frame independently of said adjustable main frame, 25 for the purpose specified.
3. In a machine of the character described, the combination of a base frame having

vertical uprights comprised of sections pivotally connected together, arc-shaped rack bars at the sides of the frame, spur gears 30 engaging said bars, and means for rotating said gears so as to cause them to ride up or down on said racks to raise or lower the frame.

4. In a machine of the character described 35 the combination of a base frame having vertical uprights comprised of sections pivotally connected together, arc-shaped rack bars at the sides of the frame, spur gears 40 engaging said bars, means for rotating said gears so as to cause them to ride up or down on said racks to raise or lower the frame, a conveyer frame mounted on said main frame and adjustable therewith, and means for adjusting the lower end of said conveyer 45 frame independently of said adjustable main frame.

In testimony that I claim the foregoing as my own, I affix my signature in presence of two witnesses.

FREDERIC S. CONVERSE.
